A. J. TIDBALL.
GUARD FOR ELECTRIC LIGHT CONNECTIONS.
APPLICATION FILED JULY 20, 1918.

Patented Mar. 18, 1919.

UNITED STATES PATENT OFFICE.

AUBREY J. TIDBALL, OF DULUTH, MINNESOTA.

GUARD FOR ELECTRIC-LIGHT CONNECTIONS.

1,297,608.

Specification of Letters Patent. Patented Mar. 18, 1919.

Application filed July 20, 1918. Serial No. 245,947.

To all whom it may concern:

Be it known that I, AUBREY J. TIDBALL, a citizen of the United States, residing at Duluth, in the county of St. Louis and State of Minnesota, have invented certain new and useful Improvements in Guards for Electric-Light Connections, of which the following is a specification, reference being had therein to the accompanying drawing.

10 This invention relates to protectors or guards for electric light socket connections and has special reference to such a guard for portable electric lights used at the terminus of a flexible wire or cable.

15 There are many places and kinds of work in which lights of this character are employed, but the embodiment here illustrated is especially designed for use in ship yards or like places where such lights are subjected

20 to hard usage.

Where lights of this kind are used in the hull of a vessel under construction, they are handled more or less carelessly and many times forced or drawn into very awkward

25 and cramped places. The result is that the wire connection at the base of the socket is frequently ruptured or the insulation worn away and the light rendered useless.

To avoid such trouble and expense is the 30 principal object of my present invention.

A further object is to provide convenient means in connection with the guard for suspending the fixture from convenient places when desired.

35 Other objects and advantages of the peculiar construction will appear in the further description of the invention.

In the accompanying drawings forming part of this application, and in which like 40 reference characters represent like parts:

Figure 1 is a side elevation of a lamp socket with one of the improved guards applied thereto, the guard being shown partly in section, and

45 Fig. 2 is a side elevation of a modified form of construction of guard.

In Fig. 1, 1 represents a common weather-proof lamp socket in which the lamp or globe 2 is screwthreadedly attached.

50 These sockets are usually attached to a heavy packinghouse or deck cable indicated at 3 and which cable comprises two wires 4 and 5 which extend within the socket and form the attachment.

55 From the point of separation of the wires 4 and 5 to some distance away from the

socket, the cable is generally reinforced by winding tape thereabout, thus somewhat increasing the diameter of the cable as at 6.

The invention comprises a shield portion 60 7, preferably of sheet metal such as galvanized iron or the like, made of a size and sufficiently long to receive the major portion of the socket 1 in its larger end and to extend beyond the base thereof far enough to protect all of the broken part of the cable caused by the separating of the wires 4 and 5.

To the exterior of the smaller inner end of the shield is attached, by being wound thereabout, one end of the spiral wire coil 8, 70 which is graduated in the diametrical measurement of its coils, from the size of the shield to which it is attached at one end, to the size of the outside measurement of the cable 3 at the opposite end.

75 The pitch of the coils may be varied in proportion to the size of the wire used, but the idea is to have the wire sufficiently stiff to prevent the cable being bent at a sharp angle at any time and thus prolong the life 80 of the socket connection.

There is no means for attaching the guard to the socket as the smaller coils of the wire are of a size to snugly fit the cable and have sufficient frictional contact therewith to hold 85 the guard up in place on the socket.

The coils of the wire surrounding the shield are preferably securely attached thereto by soldering, and adjacent the outer end of the shield, is preferably soldered a 90 suitable metal hook 9 for suspending the connection to a support when desired.

In Fig. 2 is shown a modified form of construction of guard, the entire device being composed of a single piece of wire and 95 in which a number of the larger coils are made to contact each other and securely soldered together forming a rigid shield 10, similar in general shape to the shield 7 shown in Fig. 1. At the outer end of the 100 shield portion, the end of the wire is extended as at 11 and formed into a hook, similar to and for the same purpose as the hook 9 shown in the other figure.

That part of the wire extending inwardly 105 beyond the shield as at 12, may have the coils spaced apart any desired distance to suit circumstances, the last one or two being close fitting upon the cable to hold the guard where placed.

110 From the foregoing it is evident that I have devised a simple and efficient guard

which will effectually protect and prolong the life of a portable electric socket connection to which it may be applied.

Having thus described my invention, what I claim as new and desire to secure by Letters Patent, is:—

1. The combination with a portable electric lamp socket having a tapered body portion the walls of which converge toward the 10 end of the socket to which the electric wires are attached, of a wire guard comprising a rigid tapered portion fitting neatly over the tapered portion of the socket with the inner end thereof spaced from the end of 15 the socket and a flexible portion composed of a spirally wound wire, one end being fixed to the rigid portion and the opposite end snugly fitting the electric wire.

2. The combination with an electric lamp 20 socket having a tapered body portion the walls of which converge toward the end of the socket to which the electric wires are attached, of a guard composed wholly of a spirally wound single piece of wire formed 25 into a rigid tapered portion snugly fitting over the tapered portion of the socket and a resilient tapered portion forming a continuation of the tapered rigid portion the free end of which former snugly fits the electric 30 wires substantially as and for the purpose described.

3. A guard for portable electric light sockets composed of a single piece of spirally wound wire formed into a rigid tapered body portion by the coils of wire being 35 wound closely together and a resilient body portion resulting from the coils of wire being spaced apart, the outer end of the latter portion being of a size to snugly fit the wires leading to the light socket and the outer end 40 of the former portion being of a size to snugly fit over the socket.

4. The combination with a portable electric lamp socket having a tapered body portion the walls of which converge toward the 45 end of the socket to which the electric wires are attached, of a guard composed wholly of a spirally wound single piece of wire formed into a rigid tapered portion snugly fitting over the tapered portion of the socket 50 and terminating into a laterally projecting hook and a resilient tapered portion forming a continuation of the tapered rigid portion the free end of the former snugly fitting the electric wires substantially as and 55 for the purpose described.

In testimony whereof I hereunto affix my signature in the presence of two witnesses.

AUBREY J. TIDBALL.
